[57] **CLAIM**

The ornamental design for a photographic slide projector, substantially as shown and described.

DESCRIPTION

FIG. 1 is a front elevational view of a photographic slide projector, showing my new design;
FIG. 2 is a rear elevational view thereof;
FIG. 3 is a top plan view thereof;
FIG. 4 is a bottom view thereof;
FIG. 5 is a right side elevational view thereof;
FIG. 6 is a left side elevational view thereof;
FIG. 7 is a perspective view thereof; and
FIG. 8 is a perspective view similar to FIG. 7, but with a pivoted slide viewing window swung outwardly to a different position.
